UNITED STATES PATENT OFFICE.

EMIL F. HOLINGER, OF NEW YORK, N. Y., ASSIGNOR TO E. CHASE CROWLEY, OF NEW YORK, N. Y.

ANTICREEPING DEVICE FOR RAILWAY RAILS.

Application filed March 5, 1926. Serial No. 92,401.

The invention relates to that class of anti-creeping devices in which a cylindrical rolling member is interposed between the edge of the base-flange of the rail and an inclined 5 face on an adjacent fixed portion of the tie-plate, the arrangement being such as to engage the rolling member by a pinching action in the angular space thus provided. It has been found in practice that such structures hold the rails reliably but the cost of 10 manufacture of such tie-plates is prohibitive, mainly on account of the expense involved in producing the inclined faces, and also in providing means for holding such 15 rolling member against vertical movement.

The object of this invention is to provide a device of this character which shall be simple in structure, efficient in operation, and which may be economically manufactured 20 and installed, thus avoiding the above-noted objectionable features.

The invention consists in certain novel details of construction and arrangement by which the above objects are attained, to be 25 hereinafter described and claimed.

The accompanying drawings form a part of this specification and show an approved form of the invention.

Figure 1 is a plan view showing a portion 30 of a rail supported upon and engaged with a tie-plate.

Figure 2 is a vertical section of the same parts, taken transversely of the rail, on the line 2-2 in Figure 1.

Figure 3 is a plan or top view of the rolling member alone, on a larger scale than the preceding figures.

Figure 4 is a side elevation corresponding to Figure 3.

Similar reference numerals indicate the 40 same parts in all the figures.

The rail is of standard type having the head 5, vertical web 6 and base-flanges 7 and 8, supported on a tie-plate 9 and held in 45 place thereon and to the tie, not shown, by spikes 10 in the usual or any approved manner.

On the upper face of the tie-plate, near one end, is a transverse abutment 11 extending 50 parallel with and against which the outer base-flange 7 is held against lateral movement outwardly. On the upper face of the tie-plate and oppositely disposed to the abutment 11, is a ridge 12 extending the full 55 width of the plate, and having a face 13

which is presented toward the inner adjacent base-flange 8; the face 13 is plane, perpendicular to the face of the tie-plate, and parallel with the edge of the base-flange 8. The face 13 is formed by undercutting the 60 ridge to produce an overhanging lip 17 extending toward the rail, and the same shaping operation produces a wide shallow groove 18 in the upper face of the tie-plate extending fully across the latter and reaching from 65 the face 13 of the ridge 12 to a line beneath and adjacent to the edge of the inner base-flange 8.

The rolling member 14 lies in the groove 18 and is adapted to engage the face 13 and 70 the edge of the base-flange 8, and may be of any shape adapted to increase in width as it is moved forward by the creeping movement of the rail, and is preferably elliptical in plan with the main portion of its peripheral 75 edge perpendicular to its base and is provided with vertical corrugations or teeth 16. The upper and lower margins are chamfered or beveled circumferentially as at 15 to avoid the formation of burrs or roughnesses on its 80 plane faces in the operation of producing the teeth 16.

The roller thus shaped is introduced in the parallel-sided space between the face 13 of the ridge 12 and edge of the base-flange 8; 85 it is partially rotated to engage its periphery with those surfaces and in such relation thereto as to be further partially rotated by the advance movement of the rail in the direction indicated by the arrow in Figure 1, 90 causing the required frictional bite or pinching action to increase as the angle of the major axis of the ellipse widens relatively to such surfaces, with the result that any further movement of the rail is effectually resisted and stopped. As this movement is slight the difference in length between the major and minor axes of the ellipse may be correspondingly slight, so that the cramping action against the base-flange 8 may be 100 strongly induced by an easily rotatable nearly cylindrical roller.

The overhung lip 17 serves to hold the member 14 against escape by a vertical climbing movement, and is economically produced 105 by the same milling operation which produces the groove 18 and face 13.

By making the surface 13 perpendicular to and parallel with the rail-base, the same tie-plates will serve with the rails of both 110

inbound and outbound tracks, it being only necessary to introduce the members 14 with their axes in proper angular relation to the ridges and to the base-flanges of the rails.

5. Parallelism of the surface 13 of the ridge and edge of the base-flange 8 of the rail permits the introduction of two or more rolling members 14 if desired.

10. The elliptical shape of the rotatable member effects a further important advantage in that the flatly curved sides offer surfaces of greater contact area to the ridge and base-flange than is possible with a true cylindrical form, thus insuring the strong frictional 15 engagement required to wedge the rail-base between the ridge 12 and abutment 11 and hold the rail reliably against creeping.

The groove 18 permits the rolling member 14 to be located at a lower level relatively 20 to the base-flange 8 and thus locates the zone of contact at approximately the mid-height of the rolling member and lessens the tendency of the latter to lift or tilt relatively to the tie-plate.

25. I claim:—

1. In an anticreeping device, a tie-plate adapted to support a rail, an abutment on said plate adapted to lie against the outer base-flange of said rail, a ridge on said plate adjacent to and separated from the inner base-flange of said rail, said ridge having a vertical surface presented toward said inner base-flange and parallel therewith, a groove extending from said surface to a line beneath said inner base-flange and from side to side of said plate, and a rolling member located in said groove in the space between said surface and edge of said inner base-flange, adapted to engage frictionally with said sur-

40. face and said edge, and to increase such frictional gripping action by the movement of said rail in one direction.

2. In an anticreeping device, a tie-plate adapted to support a rail, an abutment on said plate adapted to lie against the outer base-flange of said rail, a ridge on said plate adjacent to and separated from the inner base-flange of said rail, said ridge having a vertical surface presented toward said inner base-flange and parallel therewith, a groove extending from said surface to a line beneath said inner base-flange and from side to side of said plate, and a vertically corrugated elliptical rolling member located in said groove in the space between said surface and edge of said inner base-flange, 45 adapted to engage frictionally with said surface and edge.

3. In an anticreeping device, a tie-plate adapted to support a rail, an abutment on said plate adapted to lie against the outer base-flange of said rail, a ridge on said plate adjacent to and separated from the inner base-flange of said rail, said ridge having a vertical surface presented toward said inner base-flange and parallel therewith, a groove extending from said surface to a line beneath said inner base-flange and from side to side of said plate, and a vertically corrugated elliptical rolling member located in 50 said groove in the space between said surface and edge of said inner base-flange, adapted to engage frictionally with said surface and edge, and a lip on said ridge projecting from the latter above said rolling member.

60. In testimony that I claim the invention above set forth, I affix my signature hereto.

EMIL F. HOLINGER.
